[57] **CLAIM**

The ornamental design for a combined video camera with liquid crystal monitor and video tape recorder, as shown and described.

DESCRIPTION

FIG. 1 is a perspective view of the top, front and right side of a combined video camera with liquid crystal monitor and video tape recorder showing our new design;

FIG. 2 is a front elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a rear elevational view thereof;

FIG. 8 is a perspective view of the rear, bottom and right side thereof with the video tape recorder in a rearwardly directed condition; and,

FIG. 9 is a view similar to FIG. 1 with the video tape recorder in a downwardly directed condition.
